UNITED STATES PATENT OFFICE

100,380

DESIGN FOR A PENCIL

John P. Lynn, Chicago, Ill., assignor to Melrose Products Co. Inc., Melrose Park, Ill., a corporation of Illinois

Application May 21, 1936, Serial No. 62,753

Term of patent 7 years

To all whom it may concern:

Be it known that I, John P. Lynn, a citizen of the United States, residing at Chicago, in the county of Cook and State of Illinois, have invented a new, original, and ornamental Design for a Pencil, of which the following is a specification, reference being had to the accompanying drawing, forming a part thereof.

The figure is a view in elevation showing in full lines the dominant portion of a pencil embodying my new design.

I claim:

The ornamental design for a pencil, as shown and described.

JOHN P. LYNN.
